LIQUOR POURER

Patrick Kearney, 38-11 217th St.,
Bayside, N.Y. 11360

Filed Nov. 15, 1965, Ser. No. 88,081

Term of patent 14 years

(Cl. D94—3)

FIG. 1 is a top view of the liquor pourer;

FIG. 2 is a front view of the same;

FIG. 3 is a side view of the liquor pourer;

FIG. 4 is a bottom view of the pourer.

The characteristic features of my design reside in the specific configuration of the cap member associated with the neck element and in the specific appearance of the pouring spout as shown.

I claim:

The ornamental design for a liquor pourer, as shown and described.
